UNITED STATES PATENT OFFICE

ANDREW M. HUNT, OF SAN FRANCISCO, CALIFORNIA, ASSIGNOR TO THE STANDARD STOKER COMPANY, INCORPORATED, A CORPORATION OF DELAWARE

MECHANICAL STOKER

Application filed February 19, 1929. Serial No. 341,212.

My invention relates to mechanical stokers of the type comprising an oscillating fuel projecting and distributing member or so-called sweeper which acts directly to project the fuel into the firebox and distribute it over the grate or firebed; and the general object of the invention is to improve and simplify the controlling mechanism of said member or sweeper.

10 To the above and other ends which will hereinafter appear, the invention consists in the features of construction and combinations of devices and arrangements of parts herein-after described and particularly pointed out 15 in the appended claims.

The present form of the invention is more especially designed for use with a fuel sweeper adapted to oscillate within a conduit head or casing so as to gather up or collect the 20 fuel as it is advanced through the conduit system and thereafter sweep or distribute it over the firebed. With this type of oscillatory distributor or sweeper it is practically essential, in order to obtain the best results, to 25 vary its speed at different points or parts of its oscillatory movement. In the form shown the movement is in excess of a full circle, in the neighborhood of 450° in extent. During part of such movement, in the present 30 case, the distributor is moving in opposition to the fuel advancing through the conduit system at which time the sweeper movement should be relatively slow; whereas another stage of the oscillatory movement should be 35 relatively fast, this movement stopping or ending quickly or abruptly, in order to effectively project and distribute the fuel over the firebed.

Heretofore to provide for the variation in 40 the speed of this general type of distributor, the train of devices for operating it has included complicated gearing and cam mechanism, or in this specific type of distributor shown in the drawings, the mechanism comprises an eccentrically mounted pinion or 45 gearing and an intermeshing rack having a series of correspondingly varied teeth. These constructions are subject to severe strains resulting in a rapidly wearing out or 50 breaking of the parts.

In carrying out my invention I have dispensed with speed varying devices of this sort in the operating train itself and have substituted therefor means imposing a variable resistance to the action of the operating 55 train. While such means may involve different forms of construction, I have preferably employed, and have shown herein, resisting means comprising a plunger or piston connected to the operating train and reciprocating in a chamber containing fluid, preferably oil, the chamber being so shaped as to impose varying resistances to the movements of the plunger, these resistances of course being co-ordinated with the sweeper so as to 60 slow it down or speed it up at the desired points in its travel. In effect, it will be observed, there is provided a differential retarding mechanism for controlling the speed of an operative train of mechanism which would 65 otherwise run uniformly assuming the source of power to be constant, but which as a result of being combined with the retarding mechanism is variably operated.

The invention will be described in detail in 70 connection with the accompanying drawings which illustrate it in its preferred form and wherein

Fig. 1 is a fragmentary vertical sectional view of part of a mechanical stoker embodying my invention, only so much of the stoker mechanism being disclosed as is necessary to a 75 full understanding of said invention;

Fig. 2 is a horizontal sectional view taken on a plane indicated by the section line 2, 2 80 in Fig. 1 looking downward, and with the cab floor removed;

Fig. 3 is a longitudinal sectional view on an enlarged scale showing part of the operating train of the sweeper and the differential 85 retarder;

Fig. 4 is a vertical sectional view taken on a plane indicated by the section line 4, 4 90 in Fig. 3 and looking in the direction of the arrows at said line; and

Fig. 5 is a vertical sectional view taken on the plane of the section line 5, 5 in Fig. 3 and looking in the direction of the arrows at said line.

The mechanical stoker to which the inven-

tion is shown as applied is of a well known commercial type employed for locomotive engines. The cab of the engine indicated generally at 10 is supported from the rear portion of a boiler comprising a backwall or water leg 11 forward of which is the firebox 12 containing a grate 13. The backwall contains a fire door opening 14 and the cab is provided with a floor or deck 15. The locomotive is coupled or connected to a tender not shown herein, which is the source of fuel supply.

As is well understood the stoker mechanism comprises a conduit system and a feeding or conveying system, these systems being partly on the tender and partly on the locomotive and co-operating to advance the fuel from the source of supply to the firebox. The conduit system leading from the tender comprises a tubular section 16 in which is telescoped a second tubular section 17 connected by a universal joint 18 with a housing, riser or elbow member 19. Said riser at its lower end has a curved elbow 20 and as it extends upward flares or expands outward as will be clearly apparent from Fig. 2. At its upper end the riser is connected to a head or casing 21, which as herein disclosed, comprises side wall portions 22, a floor or base portion 23 and sectional cover or top 24. As a whole the head or casing projects somewhat into the fire door opening 14 of the boiler, said opening above the hinged top 24 being normally covered by a removable closure 25. The forward end of the conduit system may be suitably supported from the backwall 14, the supporting means comprising a bracket 26 connected to the riser 19 and flanges 22^a projecting laterally from the casing and suitably secured to the backwall 11 at the sides of the opening 14. The fuel feeding or conveyor system comprises flexibly connected screw conveyor sections, the forward section only being shown herein and designated by the numeral 27, this section terminating at or in the neighborhood of the elbow 20.

The screw conveyor system is rotated by a motor or engine not herein shown, as is well understood, the coal or fuel being thereby advanced through the conduit system and forced upward through the riser 19. The conduit and conveyor systems extend generally below the decks or floors of the locomotive cab and its tender, the conduit system rising above the cab deck just in rear of the boiler.

The means for receiving and distributing the fuel from the floor or table 23 of the conduit system comprises an oscillatory device or sweeping member, designated as a whole by the numeral 28, and in the form shown comprising a hub portion 29, a vertically disposed arm 30 integral therewith and extending radially outward therefrom, and horizontally disposed top and bottom flanges 31 and

32 preferably integral with the arm, the whole constituting in effect a member I-shaped in cross section. It will be understood that other forms of distributors may be used equally as well with the novel operating mechanism of my invention. 70

The sweeper is disposed so that as it rotates it will just clear the floor plate 23 and to this end is secured to the upper portion of a vertically disposed shaft 33, the hub 29 being fitted over and suitably fixed to said shaft. The shaft is arranged just outside the boiler and is supported on radial and thrust bearings 34 which, together with the shaft, are enclosed and supported within a housing 35 at the under side of the base portion or fuel plate 23. Fixed to the shaft 33 between its bearings is a pinion 36 best shown in Fig. 3. 80

The pinion 36 is comprised in the train for operating the oscillatory member or sweeper 28, said train further comprising a rack bar 37 which constantly meshes with the pinion. Secured to the left-hand end portion of the rack bar is a piston rod 38 which passes leftward through a stuffing box 39 and at its left hand end portion is secured to a piston 40 reciprocating in a chamber 41, these elements being comprised in a fluid pressure motor of suitable type for reciprocating the rack bar 37. The rack bar is disposed in an extension 35^a of the housing 35. It will be seen that the operating train comprising the rack bar 37 and the intermeshing pinion 36 which operatively connects the motor with the distributor sweeper are so constructed as to provide for uniform reciprocation or oscillation of the sweeper without any variation in its speed so long as the operation of the actuating motor is uniform. 95

In order to obtain desired variations in the speed of the sweeper, there is provided novel means in the form of variable resisting or differential retarding mechanism whereby the speed of the reciprocating rack bar 37 and of the sweeper which it actuates is controlled and varied. Said retarding means comprises a plunger or piston head 42 which is secured to the outer end of a plunger rod 43, the inner end of said rod being threaded or otherwise secured in the right-hand end of the rack bar 37 in alignment with the piston rod 38. 105

The plunger rod 43 passes through a stuffing box 44 secured to a right-hand extension 35^b of the housing 35 and which accommodates the rod 43. The plunger 42 reciprocates in a chamber 45 which is secured to the extension 35^b and is generally circular in cross section but is provided at one side with an extension 46 shaped to form a channel indicated at 47 which progressively varies in its transverse dimensions as clearly shown in Fig. 3, said channel being of greatest width at a point near each end portion of the chamber and abruptly diminishing in 110 120 125 130

one dimension therefrom to each end of the chamber 45 to form in effect a cushioning or braking space 45^a or 45^b between the piston head 42 and the respective end wall of the chamber, and thence in the opposite direction the opening gradually decreases until it is at its narrowest at the middle portion of the chamber. The chamber comprising the body portion or bore 45 and the extension 47 may 10 contain a fluid, as for example, oil. The construction is such that a variable resistance to the reciprocating or oscillating movements of the plunger 42 is set up within the chamber, this resistance in turn effecting the speed 15 at which the distributing or sweeping mechanism is operated. The retardation of course varies with the resistance set up and the speed varies inversely thereto.

Referring to the operation of the mechanism it will be understood that the fuel is advanced through the conduit system by a motor operated screw conveyor independently of the motor of the sweeper mechanism, the fuel being deflected upward by the elbow 25 20 to the head or casing 21 and thence passing or dropping on to the fuel receiving plate or base 23 where it comes within the control of the sweeper or distributor 28.

In Fig. 2 the distributor is shown at one 30 extreme or limit L of its oscillation and the parts are so proportioned and arranged that each oscillating movement is about 450° in extent, carrying the member forward a little from each extreme and then backward to 35 sweep up the fuel and then forward again to project and distribute the fuel over the firebed, the movement from the L position stopping with the sweeper at the opposite extreme position L', from which it repeats 40 its movement in reverse direction returning to the point L. During such oscillating movements the fuel flows over on to the floor of the plate or base 23 and collects thereon in the path of the sweeper and as the 45 sweeper approaches the fuel emerging from the conduit, on its return or backward movement in either direction, it is slowed down by the novel differential retarding mechanism comprising the plunger 42 and the 50 chamber 45 with its variable extension 47, the minimum speed of the sweeper being reached at a point near the extreme rear of its path of movement. From this point on the movement of the distributor is in the 55 direction of the fuel feed and is accelerated, moving rapidly forward until its forward edge reaches the front of its firing door opening, when the projection of the fuel from it into the firebox commences and continues 60 throughout the greater part of the remainder of its movement. As the distributor approaches the terminal of its stroke its movement is abruptly checked and the fuel which then remains upon it or ahead of it is thrown 65 toward a corner of the firebox, the distribu-

tor then completing its movement. The retarding mechanism is so proportioned and disposed as to effect this abrupt stopping of the distributor as it nears the end of its forward movement and to also effect the progressive retardation and acceleration of the distributor or sweeping mechanism at the desired points in its travel.

I claim:

1. In a mechanical stoker, the combination with a firebox having a firing opening therein, of a fuel casing communicating with said firing opening, means for advancing fuel to the casing, means actuated independently of said fuel advancing means for projecting and distributing the fuel from the casing into the firebox, and means for variably retarding said independently actuated means throughout its cycle of operation.

2. In a mechanical stoker, the combination with a firebox having a firing opening therein, of a fuel receiving casing communicating with said firing opening, means for advancing the fuel to the casing, a single continuously oscillating fuel distributing device for distributing the fuel from the casing into the firebox, a motor, a train of devices connecting said motor with said distributing device, and variable retarding mechanism connected with said train of devices, said retarding mechanism comprising a reciprocating plunger and a plunger chamber having an extension progressively varying throughout in dimensions transverse to the direction of movement of the plunger.

3. In a mechanical stoker, the combination with a firebox, of a fuel receiving plate, means for advancing fuel to the plate, a single continuously oscillating fuel distributing device for distributing the fuel from the plate into the firebox, a motor, a train of devices connecting said motor with said distributing device, and variable retarding mechanism connected with said train of devices, said retarding mechanism comprising a reciprocating plunger and a hydraulic plunger chamber having an extension progressively varying throughout in dimensions transverse to the direction of movement of the plunger.

4. In a mechanical stoker, the combination with a firebox having a firing opening therein, of a fuel casing communicating with said opening, means for advancing fuel to the casing, a single continuously operating fuel distributor device for distributing the fuel from the casing into the firebox, a motor, a train of devices connecting said motor with said distributing device, and variable retarding mechanism connected with said train of devices arranged to vary the speed of said distributing device throughout its cycle of operation.

5. In a mechanical stoker, the combination with a firebox having a firing opening therein, of a fuel casing communicating with said

firing opening, means for advancing fuel to the casing, means actuated independently of said fuel advancing means for projecting and distributing the fuel from the casing into the firebox, and means arranged to offer a varying resistance for variably retarding said independently actuated means throughout its cycle of operation.

6. In a mechanical stoker, the combination
10 with a firebox having a firing opening there-
in, of a fuel casing communicating with said
firing opening, means for advancing fuel
to the casing, a single continuously oscillat-
15 ing fuel distributing device for distributing
the fuel from the casing into the firebox, a
motor, a train of devices connecting said mo-
tor with said distributing device and means
arranged to offer a varying resistance for
20 variably retarding said train of devices
throughout its cycle of operation.

7. In a mechanical stoker, the combination
with a firebox, of a fuel receiving plate,
means for advancing the fuel to the plate,
a single continuously oscillating fuel dis-
25 tributing device comprising a blade I-shaped
in cross section for distributing the fuel from
the plate into the firebox, a motor, a train of
devices connecting said motor with said
blade, and a resistor connected with said
30 train of devices, said resistor being arranged
to offer a variable resistance for varying the
speed of said distributing device through-
out its cycle of operation.

In testimony whereof I affix my signature.
